(57) **CLAIM**

The ornamental design for an ant moat for a bird feeder, as shown and described.

DESCRIPTION

FIG. 1 is a front perspective view of an ant moat for a bird feeder embodying my new design;

FIG. 2 is a right elevation view of the ant moat for a bird feeder of FIG. 1, a left elevation view being substantially the same;

FIG. 3 is a front elevation view of the ant moat for a bird feeder of FIG. 1, a back elevation view being substantially the same;

FIG. 4 is a top plan view thereof;

FIG. 5 is a bottom view thereof;

FIG. 6 is a front perspective view of the ant moat for a bird feeder of FIG. 1, with the hanger in a down position;

FIG. 7 is a right elevation view thereof, the left side elevation being substantially the same;

FIG. 8 is a front elevation view of the ant moat for a bird feeder of FIG. 1, with the hanger in a down position, the back elevation view being substantially the same;

FIG. 9 is a top plan view of the ant moat for a bird feeder of FIG. 1, with the hanger in a down position;

FIG. 10 is a bottom view of the ant moat for a bird feeder of FIG. 1, with the hanger in a down position;

FIG. 11 is a front perspective view of a second embodiment of the ant moat for a bird feeder embodying my new design;

FIG. 12 is a right elevation view thereof, the left side view being substantially the same;

FIG. 13 is a front elevation view of the ant moat for a bird feeder of FIG. 11, a back elevation view being substantially the same;

FIG. 14 is a top plan view thereof;

FIG. 15 is a bottom view thereof;

FIG. 16 is a front perspective view of the ant moat for a bird feeder of FIG. 11, with the hanger in a down position;

FIG. 17 is a right elevation view thereof, the left side elevation being substantially the same;

FIG. 18 is a front elevation view of the ant moat for a bird feeder of FIG. 11, with the hanger in a down position, the back elevation view being substantially the same;

FIG. 19 is a top plan view thereof; and,

FIG. 20 is a bottom view thereof.

The portions of the bird feeder in FIGS. 1, 48, and 65 and the portions of hanger and attachments in FIGS. 1 through 7, 48 through 54, and 65 through 69 that are shown in broken lines shows the environment only, and forms no part of the claimed design.
